[57] CLAIM

The ornamental design for an electronic drag racing toy, substantially as shown and described.

DESCRIPTION

FIG. 1 is a perspective view of an electronic drag racing toy illustrating our new design;
 FIG. 2 is a top plan view thereof;
 FIG. 3 is a front elevational view thereof;
 FIG. 4 is a bottom plan view thereof;
 FIG. 5 is a rear elevational view thereof; and
 FIG. 6 is a side elevational view thereof, as viewed from the right of FIG. 3; the opposite side being substantially a mirror image thereof.
